UNITED STATES PATENT OFFICE.

HENRY L. MACK, OF ELLENSBURG, WASHINGTON.

HARROW.

SPECIFICATION forming part of Letters Patent No. 440,047, dated November 4, 1890.

Application filed June 26, 1890. Serial No. 356,794. (No model.)

To all whom it may concern:

Be it known that I, HENRY L. MACK, a citizen of the United States of America, residing at Ellensburg, in the county of Kittitas and 5 State of Washington, have invented certain new and useful Improvements in Harrows; and I do hereby declare the following to be a full, clear, and exact description of the invention, such as will enable others skilled in the art to 10 which it appertains to make and use the same, reference being had to the accompanying drawings, and to the letters of reference marked thereon, which form a part of this specification.

15 This invention has reference to harrows of the type generally represented in my patents, No. 400,697, dated April 2, 1889, and No. 421,739, dated February 18, 1890; and the present invention consists in certain improvements, hereinafter described and set forth, whereby the tooth-carrying bars are improved, the end hinge-connections of the same are rendered more durable than heretofore and equally applicable to either metal 25 or wooden bars, and the teeth are effectively clamped into position.

In the accompanying drawings, forming part of this specification, Figure 1 is a plan view of a harrow - section embodying my improvements and showing the employment of both 30 metal and wooden bars. Fig. 2 is a side view of of Fig. 1. Fig. 3 is a detail view of one of the tooth-clamping plates. Fig. 4 is a detail view of one of the end hinge-loops in connection with 35 the clamping-bar. Fig. 5 is a detail perspective view of a sectional tubular bar.

The frame is preferably formed similar to that disclosed in said patents, and consists of a single iron bar bent to form flat side parallel portions and transverse ends, the latter being turned upward. Upon each of the parallel sides are secured a series of castings *a*, each consisting of a horizontal base-plate, the ends of which are perforated for the passage 45 of bolts to secure the casting to the frame, and each of said castings is provided centrally with a vertical ear *b*, transversely perforated for the engagement of a clip-bolt *c*. The tooth-carrying bars *A A' A²* are each de- 50 signed to consist of two parallel sections, either of wood or metal, as may be found desirable, according to the character of the work

for which the harrow is designed. As shown in Fig. 1, the parallel sections of the bars *A A²* represent wooden sections, and the adjacent faces of the sections of the bar *A* are vertically notched or recessed at several points, so that each pair of recesses will present a tooth-receiving opening, in which a tooth is securely held at any adjusted vertical height by means of bolts *d d'*, which pass through said sections at either side of each tooth, and have nuts applied to their projecting ends, as shown. Instead of notching the adjacent faces of the wooden sections, as 65 stated with reference to bar *A*, oppositely-arranged metallic clamp-plates *e e'* may be arranged in the inner side, of the sections and have their vertical portions recessed or notched, while they are provided at the lower 70 and upper edges with horizontal flanges, which embrace the section on which they are supported. When such clamp-plates are employed, it will be noted that the securing-bolts also pass through them, as they are 75 pierced for such purpose. When the parallel sections are made from metal, they are comparatively thin, as shown in the construction of the two rear bars *A'*, Fig. 1, and may be thicker in order to provide for the increased difference between the parallel sections.

I prefer to construct the hinged loops *c* and connect them to the parallel sections of the adjacent bar, as shown in Fig. 4, wherein the 85 loop is represented as consisting of a long and short member, the former passing through one of the sections and seated in an opening in the other section, while the longer member passes through both sections, so that the 90 threaded projecting end may be engaged by a nut *c'*. The longer member is provided with an annular shoulder *c²*, resting against the face of the adjacent section in order to give the hinged loop proper bearing. 95

As shown in Fig. 5, it will be convenient to provide tubular bars embodying the same general principle of parallel clamp-sections. The teeth *f* are rectangular in cross-section, or at least so at their upper portions; but it 100 is preferable that they should coincide with the shape of the recesses presented for them by the sections of the bars.

The construction set forth is simple, dur-

able, and comparatively inexpensive, and the teeth can be removably, adjustably, and rigidly clamped, as will be understood.

I claim—

- 5 1. The combination, in a harrow, of the main frame having its side portions provided with perforated ears, toothed carrying-bars, and **U**-shaped clip-bolts engaging said projections and passing through said bars, and secured by nuts, substantially as set forth.
- 10 2. The combination, in a harrow, of the main frame having its side portions provided with perforated ears, tooth - carrying bars, each comprising two parallel sections, com-

panion clamp-plates between said bars, harrow-teeth, and **U**-shaped clip-bolts engaging the ears of the main frame, passing through both sections of the bars and secured by nuts to hold said clamp-plates between said bars, and also serve as a hinge-connection for the same, substantially as set forth.

In testimony whereof I affix my signature in presence of two witnesses.

HENRY L. MACK.
